UNITED STATES PATENT OFFICE.

JOHN CRAWFORD, OF PHILADELPHIA, PENNSYLVANIA.

CHECK-REGISTER.

SPECIFICATION forming part of Letters Patent No. 225,920, dated March 30, 1880.

Application filed September 17, 1879.

To all whom it may concern:

Be it known that I, JOHN CRAWFORD, of Philadelphia, in the county of Philadelphia and State of Pennsylvania, have invented certain new and useful Improvements in Check or Fare Registers; and I do hereby declare that the following is a full, clear, and exact description of the invention, that will enable others skilled in the art to which it appertains to make and use the same, reference being had to the accompanying drawings, and to the letters and figures of reference marked thereon, which form a part of this specification.

The same letters and figures of reference are used to indicate the corresponding parts.

After describing the invention, its nature and extent will be shown in the claims.

My invention is a check-registering device adapted for stores, lunch-rooms, &c., and consisting of certain simple and inexpensive mechanism, fully described hereinafter, for retaining, delivering, and recording the delivery of checks of different denominations.

In the drawings forming part of this specification, Figure 1 is a perspective view of my improved register; Fig. 2, a plan, the interior being exposed; Fig. 3, a detached view of the feed-rolls; Fig. 4, a sectional elevation; Fig. 5, a detached view of the feed-slide.

The case A of the device is divided by a partition, m, into compartments A' A², each provided with a lid or cover, it being intended to prevent access to the compartment A' except by authorized persons.

The compartment A² has one or more vertical tubes or receptacles, a, corresponding in form to that of the checks used; and at a short distance below each tube is a plate or support, t, having a central slot, t'. Below each tube is a slide, B, having a knob, b', at the forward end and inclined shoulder f near the rear, and in front of said shoulder a finger, e, extending into the slot t' above the face of the plate t.

The rear corner of the finger e is beveled at x, and a spring, d, tends to retract the slide. When checks are placed in the receptacle a the lowest will rest upon the plate t, and will be struck by the finger e when the slide B is pulled forward, and will be carried out through an opening, e, in the front of the case. On releasing the knob b', the slide will move back,

the inclined corner x of the finger e lifting the checks, so that the finger can pass beneath.

The above-described feeding arrangement is more simple and inexpensive than those heretofore employed, requiring no nice fitting or finishing, as the slides may be stamped from plates and the receptacle a cut from ordinary tubes, while two straight wires may be placed side by side to leave an intervening space, which will constitute the support t.

The registering mechanism which I have preferred to employ is constructed as follows: C' C' are the side plates of a frame, in which turn the journals of two feed-rolls, C C, and of a tape-reel, E. A guide-roll, e', is so placed that the tape D, upon which is printed a series of numbers from 1 upward, shall pass downward opposite a glass-covered opening, D', in the case.

A beveled gear, g, on the journal of the reel E engages with a gear, g', on a spindle, h, having a crank-handle or square end, so that it may be readily turned to wind up the tape. On the journal of one of the rollers C is a ratchet, j, and a bar, F, sliding in guides below said ratchet, is pressed by a spring, l, against the edge of the slide B.

A pawl, k, prevents the ratchet from turning in the wrong direction.

When the slide B is drawn forward its inclined edge f raises the bar F, which strikes a tooth of the ratchet j, and turns the latter and feed-wheels C C (which are connected by gears g² g²) until sufficient tape is drawn downward to bring another figure opposite the opening D'.

While the above-described registering mechanism is very effective, it is so simple in its character that it can be made at a very slight cost, while it is much less liable to get out of order than the ordinary dial-registers.

It will be apparent that any number of slides, receptacles, and registers may be combined in a single casing, four being shown in the drawings, and that the whole structure may be cheaply made, is durable, and not likely to get out of order.

I do not claim, broadly, the combination of the delivery-slide B, having an inclined upper edge, f, and a vertical bar operated by said inclined edge and turning the ratchet of an indicator; but

I claim—

1. The combination, in a check-register, of the receptacle *a*, the support *t*, having a slot, *t'*, the slide *B*, having a finger, *e*, extending 5 into the slot *t'*, with a beveled edge, *x*, and registering mechanism connected with the slide to be operated thereby, substantially as set forth.

2. The combination of the slide *B*, having 10 an inclined edge, *f*, bar *F*, feed-wheels *C C*, ratchet *j*, and tape *D*, passing between said feed-wheels and provided with a series of figures successively increasing, as set forth.

3. The combination of the check-receptacle, 15 delivery-slide, feed-wheels *C C*, arranged to be operated by said slides, roller *e'*, tape-reel

E, numbered tape *D*, and case *A*, having an opening, *c*, for the passage of the checks, and an opening, *D'*, for the exhibition of the tape, as specified.

4. The combination, with the check-receptacles and delivery feed-slide, of the reel, feed-wheels and operating devices, and spindle *h*, geared with the shaft of the reel, as and for the purpose set forth.

In testimony that I claim the foregoing I have hereunto set my hand this 17th day of September, 1879.

JOHN CRAWFORD.
